OTHER PUBLICATIONS

Office Action issued for Design U.S. Appl. No. 29/725,964, dated Feb. 4, 2021.

Primary Examiner — Sandra Snapp*Assistant Examiner* — Ieisha N Price(74) *Attorney, Agent, or Firm* — Meunier Carlin & Curfman LLC(57) **CLAIM**

The ornamental design for a sheet pile connector, as shown and described.

DESCRIPTION

FIG. 1 is a front perspective view of my new design; and, FIG. 2 is a side view thereof.

The sheet pile connector is shown with a symbolic break in its length. The appearance of any portion of the article between the break lines forms no part of the claimed design.
